2 SHEETS--SHEET 2.

UNITED STATES PATENT OFFICE.

JAMES W. NELSON, OF NEW YORK, N. Y.

HYDRAULIC PUMP AND PRESSURE CONTROLLING DEVICE.

No. 914,162.

Specification of Letters Patent.

Patented March 2, 1909.

Application filed October 29, 1907. Serial No. 399,740.

To all whom it may concern:

Be it known that I, JAMES W. NELSON, a citizen of the United States, and a resident of the city of New York, borough of Brooklyn, county of Kings, and State of New York, have invented certain new and useful Improvements in Hydraulic Pump and Pressure Controlling Devices, of which the following is a specification.

This invention relates to devices for generating and applying hydraulic pressure, with particular reference to devices of this class for use in locations and under conditions which make necessary frequent removal and readjustment of the jack proper in order that the pressure generated may readily be successively applied at different points.

The more common and better known types of hydraulic jacks are what may be termed entirely self-contained, that is, having the pump or pumps within the ram. It is obvious that where the work is of a nature to require several successive applications of pressure at different points in the same locality, it is desirable that the jack be divided into two distinct but connected parts, one part containing the pump or pumps and being stationary, and the other part containing the ram cylinder and ram and being readily removable from one point to another within the radius of the flexible connection. Heretofore, so far as I am aware, the necessary valves and other means for controlling the flow and pressure form a part of what may be termed the pump member, the operator of the pump being the one who regulates the time of application of the pressure, its cessation when desired, and the final relief—this usually upon signal from the operator in charge of the ram member which is located at some distance from the pump member. It will be apparent that under some not unusual conditions both operators would work under a disadvantage, particularly where the work was being done amid noisy surroundings likely to cause misunderstanding of signals. It is obvious that the man who is located at the ram, where the pressure is being applied, and who is in position to note the progress and effect of the work, should be able to quickly and positively control the application, extent and duration of the pressure, and the principal object of this invention is the pro-

tection of a separated device of this character in which the pressure-controlling means are located at the ram, or, at least, within easy access of the operator at the ram. It will be apparent that under such conditions the operator who is watching the progress and effect of the application of the pressure may temporarily check increase of the pressure, renew the same, or entirely relieve the same for removal and replacement of the ram member.

My invention will be more readily understood by reference to the accompanying drawings, forming a part of this specification, in which—

Figure 1 is a side elevation of both members of a complete device embodying my invention; Fig. 2 is a transverse central section of the jack or ram member, and Fig. 3 is a transverse central section of the pump member.

Referring now to the drawings in detail, numeral 11 refers to a suitable base plate carrying, preferably integral therewith, the cylindrical pump-block 12. This pump block 12 is provided with a bore 13 within which snugly fits the piston-rod 14 which reciprocates therein to intermittently subject to pressure the liquid in the pump chamber 15, in which said bore 13 terminates. The upper end 20 of the cylinder 12 is provided with a screw-threaded pocket to receive the packing ring 16 which is firmly pressed therein and against the rod 14 by means of the correspondingly threaded cap 17. The upper end of the cylinder 12 is exteriorly threaded to receive the interiorly threaded ring 18 carrying the yoke 19 which provides a guide for the upper end of the rod 14. The pump-block 11 is further provided with a bracket 20 to or in which is pivoted the link 21 which provides an adjustable fulcrum for the pump lever 22. The rod 14 is provided with a flattened bearing portion 23 which is pivoted within the pump lever 22, so that by means of said lever the rod 14 may be vertically reciprocated.

What I term the ram member comprises the ram cylinder 24 with the suitably closed bottom 25, and therewithin the vertically-acting ram 26 which is provided with the usual packing 27. Preferably secured to the exterior of the ram cylinder, in any suitable manner, is the valve box or cylinder 28 which I have shown provided with a substantially central valve bore 29. This valve bore 29 110

leads from an enlarged portion or chamber 33 and is increased in diameter to provide a seat 30 for a valve 31 the stem 32 of which projects upwardly into said chamber 33. Within 5 in the enlarged portion of this bore below the valve 31, I prefer to insert the valve-plug 34 (as shown and described in detail in my co-pending application filed July 8, 1907, Serial Number 382,564, and for the purposes set 10 forth therein) providing a seat for the valve 35 the stem 36 of which projects upwardly nearly but not quite to (when both are seated) the valve 31. The valve 35 is preferably spring-seated, as shown. The lower end of 15 the bore 29 is seated by means of a plug or cap 51, and from that portion of the bore below the valve 35 a duct 37 leads into the ram chamber 38. Into the chamber 33 at the upper end of said bore, preferably through 20 the medium of a connection 39, leads the passage within a pipe or other suitable conduit 40 from any suitable source of liquid supply, such as a tank or barrel of water. Similarly opening into said bore 29, between 25 the valves 31 and 35, is the passage provided by the pipe 41, said pipe being preferably of copper, lead or other soft metal whereby it may have the requisite strength to withstand the heavy pressure strains and yet be sufficiently flexible to permit of very decided 30 changes in the relative positions of pump and ram. This pipe 41 is preferably suitably secured to said valve cylinder by means of the common and well-known form of connection 35 42, and the other end thereof is provided with the connection 43 leading through the duct 44 in the pump-block into the pump chamber 15.

It will now be apparent that when the piston 40 ton 14 is raised, a partial vacuum will be formed within the chamber 15 which will result in the liquid flowing from the source of supply through the pipe 40, past the valve 31 in the valve bore 29, through the pipe 41 and 45 into the chamber 15. Upon the down-stroke of said piston, the liquid will be forced from said chamber 15 back through the pipe 41, the pressure in this case seating the valve 31 and necessitating the flow of liquid past the 50 valve 35 and through the duct 37 into the ram chamber 38, where the pressure operates to raise the ram 26 under the well-known principles of hydrostatics.

Opposite the chamber 33 the wall of the 55 valve box or cylinder 28 is provided with a screw-threaded aperture for the correspondingly threaded plug 45, within which is journaled the stud or short shaft 46 carrying, at its inner end, within the chamber 33, the 60 cam 47. The exterior end of said shaft is slotted to provide a seat for the end of the operating lever 48, by means of which the shaft and cam are rotated. The cam 47 is so located and adjusted that under normal 65 conditions the operating face thereof is clear

of the end of the stem 32 of the valve 31, and it is, therefore, non-interferent with automatic action of said valve. By rotating said shaft, the cam 47 may be made to impinge against the end of the stem 32 of the valve 70 31, first operating to positively unseat said valve, and, upon continuing depression of said valve, the latter will impinge against the end of the stem 36 and unseat the valve 35 and hold both valves off their seats. 75

It will now be apparent that the workman or operator at the ram may absolutely control the effective operation of the pump without signaling or otherwise communicating with the operator or workman at the 80 pump and irrespective of a continuation of the pumping operation beyond the desired point. When it is desired to check an increase of pressure, without relieving the existing pressure within the ram chamber, 85 the workman at the ram will throw the lever 48 to a vertical position, which causes the cam 47 to rotate just far enough to unseat the first valve only, under which conditions continuation of the pumping operation 90 merely causes the liquid to flow back and forth through the now opened passage between the pump chamber and the source of liquid supply. If additional pressure is required, the workman at the ram will turn 95 the lever back to its original position (as indicated in Figs. 1 and 2) which again permits automatic action of the valve 31 and, consequently, effective operation of the pump. When the work has been done, and 100 it is desired to remove the ram member, permanently or for readjustment in a new position, the workman at the ram will throw the lever 48 to a horizontal position oppositely directed to that indicated in Fig. 1, 105 which will effect, from the cam 47, maximum depression of the valve 31 and the consequent unseating of both valves in the bore 29, which provides an open passage from the ram chamber 38 to the source of supply. 110 The weight of the ram itself, under any ordinary conditions, will force the liquid out of said ram chamber and back into said source of supply, and this irrespective of the fact that the workman at the pump may 115 have continued the pumping operation.

The ends of a curved plate 49, secured to or integral with said valve box or cylinder 28, may provide suitable stops to prevent accidental rotation of the shaft 46, the lever 48 120 being normally in engagement with one or the other of said ends and being preferably pivoted in the end of the shaft 46 whereby, in order to rotate said shaft, it is necessary to first withdraw said lever clear of said 125 plate 49, and subsequently operate the same to rotate said shaft.

I have shown the plate 11 of sufficient length to provide a support for the platform 50, against which the end of a suitable brace 130

(not shown) may be placed to resist tendency of the pump member to tilt under action of the pumping forces. I have further shewn the ram cylinder provided with folding handles 52 52 by means of which this member may be readily moved from place to place.

Particular attention is directed to the fact that where the jack proper or ram member is 10 separate from the pump or pump member, with a flexible or other conduit therebetween, and the controlling valves are located in the usual manner in the pump member, said connecting conduit is under continuous and intermittently increasing pressure from the 15 time the pumping operation is started until the work is done and the pressure in the ram chamber relieved. Not only does this vastly increase the possibility of leakage and of 20 more serious consequences in case of accident, but it is well known that copper pipe or tubing—and such tubing is most frequently employed for this connection—acquires a certain temper from being thus subjected to 25 pressure which within a comparatively short period of time destroys its flexibility and, therefore, its usefulness for this purpose. With the valves located at what may be 30 termed the "ram end" of the connection, it will be apparent that the connecting conduit is subjected to the pressure of the liquid only when the pump is in action, not only doing away with a large proportion of the annoyance from accidents and leakage, but reducing 35 by about ninety per cent. (so far as I can determine) the time during which the pipe or conduit is subjected to pressure, thus prolonging its useful life by preventing early hardening and rigidity and the necessity for 40 frequent annealing.

Many modifications of minor details of my improved hydraulic pump and pressure controlling device will doubtless readily suggest themselves to those skilled in the art to which 45 it appertains, and I therefore do not desire to limit my invention to the specific construction herein shown and described.

I claim as new and desire to secure by Letters Patent:

50 1. In combination, means for generating hydraulic pressure, means apart therefrom and having flexible connection therewith for applying the pressure and for controlling operations of both said generating and said applying means.

2. In combination, means for generating hydraulic pressure, means apart therefrom and having flexible connection therewith for applying the pressure, and means contiguous 60 to said applying means for controlling operations of both said generating and said applying means.

3. In combination, means for generating hydraulic pressure, means apart therefrom 65 and having flexible connection therewith for

applying the pressure, and means forming part of said applying means for controlling the effect of operation of said generating means and for finally relieving the applied pressure.

4. In combination, means for generating hydraulic pressure, and means apart therefrom but connected therewith for applying the pressure, said applying means being provided with means for controlling the flow to and from said generating and said applying means.

5. In combination, stationary means for generating hydraulic pressure, relatively movable means for applying the pressure at selective points, and means forming part of said applying means for controlling the flow to and from said generating means.

6. In combination, stationary means for generating hydraulic pressure, relatively movable means for applying the pressure at selective points, and means forming a part of said applying means for controlling the effect of operation of said generating means and for finally relieving the applied pressure.

7. In combination, stationary means for generating hydraulic pressure, means movable with respect thereto for applying the pressure, and means movable with said applying means for controlling the flow to and from both said generating and said applying means.

8. In combination, a stationary pump, a relatively movable ram and means forming a part of said ram to control the flow to and from said pump.

9. In combination, a stationary pump, a relatively movable ram and means forming a part of said ram to control the effect of operation of said pump and for finally relieving the applied pressure.

10. In combination, a stationary pump, a movable ram, and means movable with said ram to control flow to and from both said pump and said ram.

11. In combination, a pump, a separate ram cylinder and ram, flexible connecting means between these two elements, and means secured to said ram cylinder for controlling the effect of operation of said pump and for finally relieving the applied pressure.

12. In combination, a stationary pump, a separate ram-cylinder and ram, flexible connecting means between these two elements, and means secured to said ram-cylinder for controlling flow to and from both the pump chamber and the ram chamber.

13. In combination, a stationary member containing the pump and a relatively movable member containing the pump valves and means for applying the pressure generated by said pump.

14. In combination, a stationary member containing the pump and a relatively movable member to apply the pressure generated

by said pump, said movable member containing the pump valves and means for their manual control.

15. In combination, a stationary member containing the pump and a relatively movable member to apply the pressure generated by said pump, said movable member containing the pump valves and being provided with means for unseating one or more of said valves.

16. In combination, a stationary pump, a relatively movable ram-cylinder and ram, a member secured to said ram-cylinder which contains a portion of the fluid-passage from source of supply to the pump chamber and to the ram chamber, suitable valves in said passage and in said members, and means for controlling said valves.

17. In combination, a stationary pump, a relatively movable ram-cylinder and ram, a member secured to said ram-cylinder which contains a portion of the fluid-passage from source of supply to the pump chamber, valves in said passage and in said member, a duct leading from said passage below said valves to the ram chamber, and means for controlling said valves.

18. In combination, a stationary pump, a

relatively movable ram-cylinder and ram, a member secured to said ram cylinder which contains a portion of the fluid-passage from source of supply to the pump chamber, suitable pump and pressure valves in said passage and in said member, a duct leading from said passage below said valves to the ram chamber, and means for positively unseating one of said valves, said means being further operable to unseat all of said valves.

19. In combination, a stationary pump, a relatively movable ram-cylinder and ram, a member movable with said ram-cylinder which contains a portion of the fluid-passage from source of supply to the pump chamber, suitable valves in said passage in said member, a duct leading from said passage below said valves to the ram chamber, said member being provided with means for positively unseating one or all of said valves.

In testimony of the foregoing, I have hereunto set my hand in the presence of two subscribing witnesses.

JAMES W. NELSON.
